his Attorney

UNITED STATES PATENT OFFICE.

JOHN G. CARRIER, OF HICKORY, NORTH CAROLINA.

COMBINED DADOING AND RELISHING MACHINE.

Application filed May 7, 1924. Serial No. 711,728.

My invention relates to wood-working machines and its principal object is to provide a machine for simultaneously da-doing and relishing both ends of sash rails or other pieces of wood.

A further object of the invention is to provide a machine of this character which is automatic in operation and will do the work automatically and accurately.

It is also an object of the present invention to provide a machine of this type which will operate on both ends of the length of wood at the same time and which is capable of being adjusted to lengths of wood of various dimensions.

With the preceding and other objects and advantages in mind, the invention consists of the novel combination of elements, constructions and arrangement of parts and operations to be hereinafter specifically referred to, explicitly claimed and illustrated in the accompanying drawing wherein:

Figure 1 is a top plan view of a da-doing and relishing machine constructed in accordance with my invention,

Figure 2 is a side elevation of the same,

Figure 3 is a perspective of one of the door or window stiles after being operated on by the machine,

Figure 4 is an end elevation of the machine, and

Figure 5 is a vertical sectional view taken on line 5—5 of Fig. 2.

Referring to the drawings in detail, wherein corresponding characters of reference denote like parts throughout the several views, the numeral 5 denotes a supporting table including longitudinally horizontal sills 6 and pairs of supporting legs 7. Extending transversely of the beam 6 at the ends thereof are plates 8 and 9, the plate 9 being rigidly attached to these sills 6 while the top rails of the frame are tubes 10 which are perforated on their top side to receive a round toothed sprocket thereby permitting the plate 8 to be adjusted toward and away from the plate 9. Pairs of bearings 11 are mounted on the plates 8 and 9 in longitudinal alinement and in which a main drive shaft 12 is journaled, the latter carrying drive pulleys 13 adapted to be driven by a belt from any desirable source or power, not shown. Journaled in the bearings 11 on the plate 8 and through which the shaft 12 passes is a relatively short tubular shaft 13

having driving connection with the shaft 12 by means of a spline 14. Journaled on the plates 8 and 9 are horizontally disposed shafts or stocks 15 carrying rotary bits or relishing tools 16 at their inner ends. The 60 opposite ends of these shafts or stocks 15 are provided with pinions 17 which are driven by drive pinions 18 fixed to the shaft 12. Also journaled on the plates 8 and 9 and disposed horizontally at the forward ends 65 thereof are shafts 19 carrying cutter or da-doing heads 20, these shafts 19 being disposed at right angles to the shafts 15. In order to drive the da-doing heads 20, drive belts 21 are engaged with the shafts 19 and 70 drive pulleys 22 fixed to the main drive shaft 12.

In order to shift the plate 8 toward and away from the plate 9 the following mechanism is provided: Depending from the plate 75 8 are bearings 23 in which a shaft 24 is journaled, the latter carrying at its ends sprocket or round toothed gears 25 which engage holes drilled in the upper face of the tubes that also act as ways or supports or 80 sills. It follows that upon rotation of the hand wheel 28 the shaft 24 will be rotated, thereby causing the sprockets 25 to traverse the tubular ways 10 to shift the plate 8 laterally on the tubular sills. 85

Journaled in the table 5 and below the sills 6 is a longitudinally extending shaft 31 carrying disks 32 at the ends thereof and a relatively large pinion 33 adjacent one end thereof. A small shaft 34 is journaled in 90 the table 5 below the shaft 31 which carries a drive pulley 34 driven by the drive belt 35 from the shaft 12. A small drive pinion 37 is also fixed to this shaft 34. Journaled in the frame 5 and in horizontal alinement with the shaft 34 is a shaft 38 having pinions 39 and 40 fixed thereto; the pinion 40 meshes with the pinion 37 while the pinion 39 meshes with the pinion 33 to drive the shaft 31. 95

Extending transversely of the sills 6 at the ends thereof and projecting outwardly from the forward side of the table 5 is a pair of guide rails 41 upon which channel-shaped slides 42 are mounted for reciprocatory 105 movement. Fixed to the upper faces of the carriages 42 and extending longitudinally across the top of the table 5 is a work carriage 43. The upper face of the slides 42 are formed with longitudinal grooves which 110

are enlarged at their bases and receive the heads or bolts 45 carried by the ends of the work carriage or carrier 43. Nuts 45' are threaded on the upper ends of these bolts 5 which are adapted to be loosened to permit the bolts to be shifted to any position in the slots to adjust the carriage or work carrier 43 relative to the slides 42 to accommodate door or window stiles or other wooden members of various widths. Eccentrically connected with the disks 32 are pitmen 46 having operative connection with the slides as indicated at 47.

Fixed to the opposite faces of the plates 15 8 and 9 and disposed between the carriage or work carrier 43 and adapted to support the ends of the stiles or other work indicated at W are angle irons 48, the latter being secured to the plates 8 and 9 by means of slot 20 or bolt connections 50 to permit these plates to be adjusted vertically to accommodate wood of various thicknesses.

Fixed to the carriage or work carrier 43 at its longitudinal center and extending at 25 right angles thereto is an arm 51 which underlies the work and terminates in an up-standing abutment 52 at its inner end adapted to engage the work to pull the same way from the relishing tools and da-doing heads 30 as the work holder or carriage moves away from the latter.

The operation of the machine is as follows: The drive shaft 12 being driven from any suitable source rotates the relishing bits and 35 da-doing heads and through the medium of the gearing above mentioned reciprocates the carriage or carrier 43 toward and away from the relishing bits and da-doing heads. As the carriage moves toward the relishing bits 40 and da-doing heads the work resting on the angle irons 48 is moved into engagement with these tools and remains in such position long enough for the ends of the wood to be chipped off or da-doed and at the same 45 time the relishing bits perform the relishing or grooving of the work. As the carriage or work carrier 43 moves away from the tools the work is engaged by the abutment 52 and moved outwardly away from the tools to permit 50 the operator to remove the same from the machine and place a new piece of work in position for operation.

It is understood that the form of my invention herein shown and described is to be 55 taken as a preferred example of the same, and that various changes in shape, size and arrangement of parts may be resorted to without departing from the spirit of the invention or the scope of the subjoined claims.

Having thus described my invention, which I claim as new and desire to secure and protect by Letters Patent of the United States is:

1. In a wood working machine, the combination of a table having longitudinal sills,

a plate fixed to said sills near corresponding ends thereof, rails resting upon the opposite end portions of said sills, a second plate movably supported by said rails, means for adjusting the latter plate toward the former 70 plate, aligned shafts journaled upon the plates and extending longitudinally of the table, cutters carried by the inner ends of said shafts between the plates, other shafts journaled upon the plates at right angles to 75 said first mentioned shafts and in a plane therewith, cutters carried by the inner ends of the latter shafts to extend between the plates immediately in front of said first mentioned cutters, a work carrier movable 80 toward and away from said cutters, and means for rotating said shafts.

2. In a wood working machine, the combination of a table having longitudinal sills, a plate fixed to said sills near corresponding 85 ends thereof, tubular rails resting upon the opposite end portions of said sills and provided with longitudinally spaced openings, a second plate movably supported by said rails, a shaft journaled upon the latter plate and 90 provided with sprockets having the teeth thereof disposed for engagement in said openings whereby the shaft may be turned for adjusting the latter plate relative to the former plate, aligned shafts journaled upon the plates and extending longitudinally of the table, cutters carried by the inner ends 95 of the latter shaft between the plates, other shafts journaled upon the plates at right angles to said second mentioned shafts and in 100 a plane therewith, cutters carried by the inner ends of said last mentioned shafts to extend between the plates immediately in front of said first mentioned cutters, a work carrier movable toward and away from the cutters, and means for rotating said cutter carrying shafts.

3. In a wood working machine, the combination of a table having longitudinal sills, a plate fixed to said sills near corresponding 110 ends thereof, rails resting upon the opposite end portions of said sills, a second plate movably supported by said rails, means for adjusting the latter plate toward the former plate, aligned shafts journaled upon the 115 plates and extending longitudinally of the table, cutters carried by the inner ends of said shafts between the plates, other shafts journaled upon the plates at right angles to said first mentioned shafts and in a plane 120 therewith, cutters carried by the inner ends of the latter shafts to extend between the plates immediately in front of said first mentioned cutters, slides shiftable transversely of the table, a cross bar extending between said slides to provide a work carrier, the slides being provided with grooves, fastening devices extending through said bar and having heads slidably received in 125 said grooves whereby the bar may be ad- 130

justed longitudinally of the slides, means for rotating said cutter shafts, and means for reciprocating said slides in unison.

4. In a wood working machine, the combination of a table having longitudinal sills, a plate fixed to said sills near corresponding ends thereof, rails resting upon the opposite end portions of said sills, a second plate movably supported by said rails, means for 10 adjusting the latter plate toward the former plate, aligned shafts journaled upon the plates and extending longitudinally of the table, cutters carried by the inner ends of said shafts between the plates, other shafts 15 journaled upon the plates at right angles to said first mentioned shafts and in a plane therewith, cutters carried by the inner ends of the latter shafts to extend between the plates immediately in front of said first 20 mentioned cutters, slides shiftable transversely of the table, a cross bar rigidly connected to said slides to provide a work carrier, an arm carried by said cross bar to receive the work and projecting between said 25 plates, said arm being provided at its inner end with a stop for retracting the work, brackets fixed to the confronting edges of said plates to slidably support the ends of the work resting on said arm, means for rotating 30 said cutter shafts, and pitmen driven

by said last mentioned means and connected with the slides for reciprocating said slides in unison.

5. In a wood working machine, the combination of a table having longitudinal sills, 35 a plate fixed to said sills near corresponding ends thereof, rails resting upon the opposite end portions of said sills, a second plate movably supported by said rails, means for adjusting the latter plate toward the former 40 plate, aligned shafts journaled upon the plates and extending longitudinally of the table, cutters carried by the inner ends of said shafts between the plates, other shafts journaled upon the plates at right angles to 45 said first mentioned shafts and in a plane therewith, cutters carried by the inner ends of the latter shafts to extend between the plates immediately in front of said first mentioned cutters, a work carrier movable 50 toward and away from said cutters, bearings carried by said second mentioned plate, a tubular shaft journaled by said bearings, a driving connection between said tubular shaft and one of said cutter shafts, a drive 55 shaft splined in said tubular shaft for driving said tubular shaft, and driving connections between said drive shaft and the other of said cutter shafts.

JOHN G. CARRIER.
